United States Patent Office

Des. 183,641

Patented Sept. 30, 1958

183,641

LETTER OPENER

Frank A. Werstein, Long Beach, Ind.

Application March 31, 1958, Serial No. 50,250

Term of patent 14 years

(Cl. D74—1)

Fig. 1 is a side elevational view of a letter opener showing my new design;

Fig. 2 is a similar view but with the blade turned 90° to provide an edge view;

Fig. 3 is a top plan view; and

Fig. 4 is a bottom plan view thereof.

I claim:

The ornamental design for a letter opener, substantially as shown.
